UNITED STATES PATENT OFFICE.

CHARLES A. HULTQUIST, OF LOS ANGELES, CALIFORNIA.

DRILL-STEEL-RETAINING DEVICE.

1,253,828.

Specification of Letters Patent. Patented Jan. 15, 1918.

Application filed March 26, 1917. Serial No. 157,350.

To all whom it may concern:

Be it known that I, CHARLES A. HULTQUIST, a citizen of the United States, residing at Los Angeles, in the county of Los Angeles and State of California, have invented a new and useful Drill-Steel-Retaining Device, of which the following is a specification.

This invention relates to devices of the character designed to prevent the drill steel from becoming detached from the chuck in which it is loosely seated, as in various types of drilling machines, and an object of this invention is to produce a device of this character of simple construction and one that is easily and quickly thrown into and out of commission so that the drill steel can be quickly attached and detached.

Another object is to produce a device of this character which is more or less yielding axially of the drill steel which it is to retain so that in drilling when the drill steel strikes comparatively soft material or penetrates a hole or crevice in the rock the blow of the hammer on the drill steel will be absorbed to some extent by the drill steel retainer so as to minimize liability of breakage of the retainer and the parts of the drilling machine with which said retainer is connected.

Another object is to provide a construction which will enable the driller to readily grasp the device for throwing it into and out of commission.

Another object is to so construct the device that a comparatively small amount of pressure exerted by the driller's hand will release the drill steel retaining member so that it can be readily swung out of drill steel retaining position.

In so far as the foregoing objects are concerned this application is a continuation of my co-pending application for patent for pneumatic tool filed July 3, 1916, Serial No. 107,361.

A further object of the invention is to facilitate attaching and detaching of the drill steel retaining member from its bracket without detaching the bracket from the drilling machine.

Other objects and advantages will appear in the subjoined detail description.

The accompanying drawings illustrate the invention:

Figure 1 is a side elevation of a drilling

machine equipped with the improved drill steel retaining device.

Fig. 2 is an enlarged elevation of the drill steel retaining device from the right of Fig. 1, the lower portion of the drilling machine 60 also being shown.

Fig. 3 is a view similar to Fig. 2, portions being shown in vertical mid section for clearness of illustration.

Fig. 4 is a plan view of Fig. 2.

Fig. 5 is a plan section on line indicated by x^5-x^5 , Fig. 3.

In Fig. 1 the drill steel is indicated at 1 and is provided as usual with a shoulder or abutment 2 spaced apart from its head and which is inserted in a barrel 3 of a drilling machine indicated in general by the character 4. The drilling machine 4 in the instance shown is of the type employed for drilling down holes, but it is understood that 75 the invention is applicable to other types of drilling machines. The drill steel 1 can readily slide in and out of the barrel 3, as is usual and readily understood, and to retain the drill in place so that it cannot become detached from the drilling machine, unless desirable, the outer face of the abutment 2 engages a semicircular abutment 5 which partly surrounds the drill steel when said drill steel is in place as in Fig. 1. 85

The semicircular abutment 5 forms the intermediate portion of a U-shaped member which also comprises arms 6. The arms 6 are provided with curved or semicircular intermediate portions 7, curved portions 8 connecting the portions 7 to the semicircular portion 5, straight portions 9 and outwardly bent end portions forming pivots 10 for the arms, said pivots being detachably inserted in pivot seats in the form of perforations 11 95 in lugs 12 of a bracket 13.

The arms 6 and semicircular abutment 5, in the instance shown in the drawings, are integral with one another and are formed of a rod, bar or heavy wire so as to be more or less rigid yet having more or less spring quality and capable of being sprung together so that when so sprung the pivots 10 can be withdrawn from the perforations 11; and capable of being sprung to some extent 105 axially of the drill steel 1 so as to absorb shocks transmitted from the abutment 2 to the circular abutment 5 when the drilling machine is in operation.

The bracket 13 is connected with the bar- 110

rel 3 of the drilling machine and, in the instance shown, for the connection said bracket comprises besides the lugs 12 a collar 14 having an axial perforation 15. The 5 barrel 3 is in sections, one section 16 having a reduced portion 17 adapted to fit in the perforation 15 and inside of another barrel section 18. At the inner end of the reduced portion 17 is an annular shoulder 10 19 and the bracket collar 14 seats between said shoulder 19 and the adjacent end of the barrel section 18 when the sections 16, 18 are assembled as clearly shown in Fig. 3. The collar 14 is provided with an outstanding 15 ear 20 having a notch 21 to accommodate one of the bolts 22, said bolts 22 being of the character commonly employed in drilling machines for holding the barrel sections together in a manner well understood 20 in the art and therefore not necessary to describe in detail herein. It is readily seen from the foregoing that owing to the bolt 22 and notch 21 the collar 14 and its lug 12 are prevented from turning relative 25 to the barrel of the drilling machine.

The arms 6 when in position parallel with the axis of the drill steel and therefore in drill-retaining position, as in Fig. 1, are held against swinging away from said position by reason of the outer faces of the straight portions 9 of the arms engaging grooves 23 on the inner faces of the lugs 12. The arms 6 being of spring material, it is clear that by the construction just described 30 said arms cannot become accidentally detached from the bracket but may be readily turned, when sprung out of the grooves 23, so as to bring the abutment 5 to one side of the device to permit removal of the drill 35 steel 1 when such removal becomes desirable.

The distances between the inner faces of the arms 6 and the barrel 3 are less than the lengths of the pivots 10 so that when the arms 6 are either in their drill-retaining 40 position or in the drill-releasing position indicated at *a*, Fig. 1, the pivots 10 cannot be disengaged from the perforations 11.

The foregoing described construction is a continuation of the hereinbefore mentioned 45 co-pending application for patent.

It may be desirable, in case of breakage of the drill-steel retaining member 5, 6 or for other reasons, to attach or detach the drill-retaining member, and for that purpose the 50 inner faces of the lugs 12 are provided at right angles to the grooves 23 with grooves 55 24 extending from the pivot seats 11 to one longitudinal edge of the lugs 12. These grooves 24 are in such position that when 60 the drill-retaining member 5, 6 is turned to the position indicated in dotted lines *b*, Fig. 1, the pivots 10, after springing the arms 6 toward one another, can be withdrawn from the perforations 11 through the grooves 24 65 for the reason that the distances from the

bottom of the grooves 24 to the barrel 3 are greater than the lengths of the pivots 10.

In practice, when it is desired to detach the drill from the drill-retaining member 5, 6, said member will be swung from the position shown in solid lines in Fig. 1 to the position indicated at *a*, thus freeing the abutment 2 of the retaining abutment 5, and allowing the drill to be withdrawn from the barrel. When it is desired to insert the 75 drill steel the foregoing operations will be reversed so as to bring the drill retaining member to the position shown in solid lines in Fig. 1.

When it is desired to detach the drill-retaining member 5, 6 the operator, after removing the drill steel 1 as above explained, will move the drill-retaining member 5, 6 to the position indicated at *b* to bring the straight arm portions 9 in registration with 80 the grooves 24, and he will press the arms 6 toward one another sufficiently to withdraw the pivots 10 from their seats 11 and he will then draw the arms 6 away from the lugs 12 so as to move the pivots away from their 85 seats through the grooves 24.

To insert the drill-retaining member 5, 6 a reversal of the operation just described will be effected.

It is clear that when the drill-retaining 90 member is in drill-retaining position any blow on the drill steel 1 delivered by the machine in a manner well understood in the art, if the abutment 2 comes into engagement with the abutment 5, will be absorbed to a 100 great extent by the curved portions 7 of the arms as they are sufficiently resilient to spring to some extent axially of the drill steel 1.

By forming the notches 23 at the outer 105 faces of the arms 6 it is clear that the operator may readily release the arms from the notches with one hand by grasping the arms between the thumb and forefinger of one hand and forcing said arms toward one another, thus the advantage of such construction is that it simplifies the operation of moving the drill steel retainer in and out of the drill steel holding position.

The foregoing will enable those skilled 115 in the art to which the invention pertains to make and use said invention, and it is understood that changes may be made within the spirit and scope of the appended claims and that the elements in said claims are subject to the doctrine of equivalents.

I claim:

1. The combination with the barrel of a drilling machine, of a bracket supported by the barrel and provided with lugs having 125 grooves in their inner faces, resilient arms pivoted in the lugs and adapted to engage the grooves to hold said arms parallel with the barrel, and an abutment connecting said arms to one another and adapted to engage 130

the abutment on a drill steel to retain said drill steel.

2. In combination, a sectional drilling machine barrel, means to hold the sections together, one of said sections having a reduced portion inserted in the other section, a collar on the reduced portion, and drill-retaining means connected with the collar.
3. In combination, a sectional drilling machine barrel, bolts to hold the sections together, one of said sections having a reduced portion inserted in the other section, a collar on the reduced portion having means to engage the bolts, and drill-retaining means connected with the collar.

4. The combination with the barrel of a drilling machine, of a U-shaped drill-retaining member comprising spring arms pivotally connected with the barrel and comprising an abutment to engage the abutment on a drill steel, said arms having semi-circular portions and curved portions connecting the semi-circular portions with the first named abutment, and means at the outer face of the arms to detachably hold said arms in drill-retaining position.

5. A drill steel retaining device of the character described comprising a bracket

having lugs provided with grooves on the inner faces, and a drill-retaining member pivoted in the lugs and adapted to engage the grooves when the member is in drill-retaining position.

6. The combination with the barrel of a drilling machine, of a bracket having lugs provided with pivot seats and with grooves on the inner faces of said lugs, and a drill-retaining member having pivots in the pivot seats and adapted to engage the grooves when the member is in drill-retaining position, there being other grooves on the inner faces of the lugs respectively extending from the perforations to one edge of the lugs, the distances between the bottoms of the first named grooves and the barrel being less than the lengths of the pivots and the distances between the bottoms of the second named grooves and the barrel being greater than the lengths of the pivots.

Signed at Los Angeles, California, this 19th day of March, 1917.

CHARLES A. HULTQUIST.
